JEFFERSON DAVIS PACE, OF ALEXANDRIA, LOUISIANA, ASSIGNOR TO PACE GARMENT SUPPORTER, INC., OF RAPIDES PARISH, LOUISIANA, A CORPORATION OF LOUISIANA

GARMENT SUPPORTER

Application filed November 7, 1928. Serial No. 317,757.

This invention relates to garment supporters and among other objects, aims to provide an improved supporter adapted to be attached to a shirt or waist to hold up trousers or other garments.

In the accompanying drawing,

Fig. 1 is a fragmentary perspective view showing the preferred form of supporter applied to a shirt for supporting a pair of trousers;

Fig. 2 is a front elevation of the supporter;
Fig. 3 is a sectional view showing how the fastener is applied to the shirt;
Fig. 4 is a vertical, central sectional view showing how the supporter is applied to a trouser button.

Referring particularly to the drawings, the supporter there shown is in the form of a substantially rectangular plate 10 of stiff material having provision adjacent to both ends to be attached to a shirt or waist. For this purpose, the plate is provided with narrow-necked slots 11 having relatively wide button openings near the bottom of the plate and arranged to receive cooperating fastener buttons 12 secured to the plate by means of flexible strips 13 which pass around the lower edges of the slots. The arrangement is such that the buttons may be threaded through the slots to engage a doubled portion of the shirt or waist and grip it in the manner shown in Fig. 3.

Between the button and slot fasteners there is shown an open button engaging slot 14 through the upper edge of the plate, the opening being flared outwardly to facilitate easy engagement with a button such as one of the suspender buttons on a pair of trousers. The lower part of the slot 14 is shown as being somewhat elongated lengthwise of the plate to permit the button to slide back and forth incident to body movements of the wearer. The arrangement is such as to promote the comfort of the wearer without causing his shirt to be twisted about his body due to walking movements or slight twisting action of the trousers or the like. Figure 4 discloses the mode of attachment of the fastener to a suspender button as just described.

If it is desired to support other garments

such as socks or stockings by means of the supporter, an ordinary elastic strap or band 15 may be threaded through a suitable slot 16 arranged near the bottom of the plate between the button and slot fasteners. To the lower ends of the elastic strap or band there may be secured an ordinary button and loop fastener 17 to engage a sock or stocking, the arrangement being such that the effective length of the strap may be adjusted by the usual button slide 18 on the rear run of the strap. It will be understood that one or more such supporting straps may be suspended from each plate.

In applying the supporter to a shirt, the wearer first grasps a portion of the shirt at a point adjacent to one of the suspender buttons on his trousers and folds the fabric so that the buttons 12 may engage behind the folded portion and secure it within the narrow neck portions of the slots, the buttons projecting forwardly through the slots so that they do not cause any discomfort to the wearer. The suspender button on the trousers is then brought over the button-receiving slot 14 and slipped into it so that it can work back and forth in the wide lower portion of the slot. The widened portion of the slot below the button-receiving portion serves to prevent the button from becoming accidentally disengaged from the slot incident to body movements which slacken the trousers and tend to lift the button out. If the sock supporter is used in conjunction with the plate it may be applied in the well known manner. However, it is understood that the sock supporting strap may be dispensed with if it is not needed.

Obviously, the present invention is not restricted to the particular embodiment thereof herein shown and described.

What I claim is:—

A garment supporter of the class described comprising, in combination, a substantially rectangular rigid plate having button and slot fasteners near its opposite ends; a suspender button-receiving slot through the upper edge of the plate between said button and slot fasteners, said suspender button-receiving slot being flared outwardly at the up-

per edge of the plate and presenting a relatively wide bottom portion to permit movement of the suspender button longitudinally of the plate incident to the movements of the wearer.

5 In testimony that I claim the foregoing as my own, I have hereto affixed my signature.

JEFFERSON DAVIS PACE.
